FLOUR SIFTER CASING

Herbert Velke, Uzwil, Switzerland, assignor to Gebrueder Buchler, a Swiss firm

Application November 30, 1954, Serial No. 33,328

Term of patent 7 years

(Cl. D55—1)

Fig. 1

Fig. 1 is a front perspective view of a flour sifter casing embodying my new design, and

Fig. 2 is a rear perspective view thereof.

The top portions of the flour sifting casing not shown are substantially plain.

I claim:

The ornamental design for a flour sifter casing, substantially as shown and described.
